SHOE OR SIMILAR ARTICLE

Roy Maling, Brookline, Mass.

Application June 2, 1954, Serial No. 30,777

Term of patent 3½ years

(Cl. D7—5)

Fig. 1.

Fig. 2.

Fig. 3.

Fig. 1 is a side elevation of a shoe showing my new design, both sides of the shoe being substantially the same;

Fig. 2 is a bottom plan view thereof; and

Fig. 3 is a rear elevation thereof.

The characteristic features of my new design are shown in full lines.

I claim:

The ornamental design for a can opener, substantially as substantially as shown and described.
